UNITED STATES PATENT OFFICE.

WILLIAM C. FARNUM, OF ARLINGTON, VERMONT, ASSIGNOR TO WYCKOFF, SEAMANS & BENEDICT, OF ILION, NEW YORK, A CORPORATION OF NEW YORK.

TYPE-WRITING MACHINE.

No. 902,525.

Specification of Letters Patent.

Patented Oct. 27, 1908.

Application filed June 30, 1903. Serial No. 163,685.

To all whom it may concern:

Be it known that I, WILLIAM C. FARNUM, citizen of the United States, and resident of Arlington, in the county of Bennington and State of Vermont, have invented certain new and useful Improvements in Type-Writing Machines, of which the following is a specification.

My invention relates to typewriting machines and more particularly to tabulating mechanism therefor; and the object of my invention is to provide simple and efficient mechanism of the character specified.

To the above and other ends which will hereinafter appear my invention consists of the features of construction, arrangements of parts and combinations of devices to be hereinafter described and claimed.

In the accompanying drawings wherein like reference characters indicate corresponding parts in the various views, Figure 1 is a side elevation with parts in section of sufficient number of parts of one form of typewriting machines with the features of my invention shown applied thereto. Fig. 2 is a rear elevation of the same with parts in section. Fig. 3 is an enlarged detail plan view partly in section and showing portions of the escapement and tabulating mechanisms. Fig. 4 is a detail rear end view of a portion of the tabulating mechanism. Fig. 5 is a detail fragmentary perspective view with parts broken away of a portion of the escapement mechanism. Fig. 6 is an enlarged detail rear elevation of the escapement wheel. Fig. 7 is an enlarged detail perspective view of the escapement dogs.

Fig. 8 is a detail rear elevation of a portion of the tabulating mechanism. Fig. 9 is a like view of the same showing a different disposition of the parts. Fig. 10 is a detail rear elevation of a part of a tabulating mechanism to be hereinafter more fully described. Fig. 11 is a detail horizontal sectional view showing portions of the tabulating mechanism and escapement devices; the section being taken on the line $x-x$ of Fig. 2. Fig. 12 is a detail fragmentary perspective view showing the front end of the tabulating key lever. Fig. 13 is a side elevation, partly in section, of a tabulating key and stem, the view illustrating the connection between said key and its key lever. Fig. 14 is a like view of the same taken at right angles to the position shown in Fig. 13. Fig. 15

is a detail perspective view showing the forward end of the tabulating key lever with the tabulating keys connected thereto. Fig. 16 is a detail plan view of the securing ring for a key head. Fig. 17 is an enlarged detail transverse sectional view of a key head, the section being taken on the line $y-y$ of Fig. 15. Fig. 18 is an enlarged detail perspective view with parts in section of the arresting abutments and guides, for the stems of the tabulating keys. Fig. 19 is a fragmentary detail plan view of the guide block and illustrating guiding walls and arresting abutments.

I have shown my invention applied to a No. 6 Remington machine though obviously the invention may be applied to other characters of typewriting machines.

The frame of the machine comprises a base 1, corner posts 2 and a top plate 3, which latter has upwardly extending supports or lugs 4 and 5 that support the guide or traverse rods 6 and 7 respectively. A shift rail supports a traverse roller 9 which is connected to a platen frame 10 that carries a platen 11, the platen frame being connected by links 12 to the carriage truck 13, provided with traverse rollers 14 which coöperate with the rod 6 to support the carriage and guide it in its movements from side to side of the machine. Extending rearwardly from the truck is a guide arm 15 which connects with a sleeve 16 that surrounds the traverse rod 7, in order to assist in supporting the truck and guiding it in the movement of the carriage from end to end of the machine.

A fulcrum bar or web 17 extends downwardly from the base plate of the machine and coöperates with the notched portions of the rear ends of the key levers 18 which are provided at their forward ends with finger keys 19 and are restored to their normal positions by the restoring springs 20. Each key lever has pivoted thereto at 21, a connecting link 22 which is connected at its upper end 23 to the crank arm of a type bar 24; it being understood that the usual number of type bars and key levers are employed though only a single type action is shown.

Extending under the various key levers is a universal bar 25 connected at its ends to upwardly extending links 26 supported at their upper ends on a transverse bar 27. This bar is connected to a forwardly ex-

- tending arm 28 on a rock shaft 29 mounted in bearings 30 of a bracket plate 31 which is secured to the top plate of the machine. A spring 32 is connected at one end 33 to the bracket plate and at its opposite end is connected by any suitable means to the rock shaft 29 and exerts a pressure to restore the rock shaft and the parts connected thereto to their normal positions.
- 10 A bearing piece or block 34 is apertured to receive a reduced portion 35 of the rock shaft and is adapted to be adjusted around the same and to be maintained in its adjusted position. Thus the arms 34 are formed by a bifurcation which extends transversely of and separates them and a screw 36 extends through threaded openings in the depending arms and is effective to draw the arms together and thus secure the bearing piece by frictional contact in its adjusted position on the shaft. Rigidly connected to the bearing piece is an upwardly extending arm 37 which is split at its upper end to form oppositely extending fingers 38 and 39.
- 15 The finger 39 is seated in a recess 40 of a lever 41 which is pivoted at 42 on the top plate of the machine and has one end of a spring 43 connected thereto at 44, the opposite end of said spring being connected at 45 to a pin which projects from a fixed bearing 46.
- 20 The lever 41 has a disk 47 seated and securely fastened in an opening or depression therein, said disk being apertured at 48 to provide stops or abutments 49 and 50.
- 25 Projecting into the space 48 between the abutments 49 and 50 is a finger 51 that projects downwardly from the feed dog 52 secured to a rock shaft 53 which is adapted to turn in bearings 54 forming a part of the bearing 46 hereinbefore referred to. The feed dog 52 has an upwardly extending bifurcated portion that forms stops 55 and 56 between which is received a headed pin 57 that projects laterally from and is carried by a loose dog 58 that is free to turn on the rock shaft 53. A spring 59 is connected at one end 60 to the fixed dog 52 and at its other end 61 to the loose dog 58, and the tension of this is exerted to normally maintain the loose dog in the position illustrated in Fig. 7 with the stop pin 57 bearing against the abutment or stop 55 carried by the fixed dog. The dog 58 has an engaging nose 62 that co-operates with the teeth of a feed or escapement rack, circular or straight, and which in the present instance is shown as an escapement wheel 63, whereas the fixed dog 52 has an engaging nose or surface 64 that likewise co-operates with the teeth of the escapement wheel; the engaging nose of both dogs moving radially towards and away from the escapement wheel and into and out of engagement with the teeth thereof. The engaging nose 62 of the loose dog normally engages the es-

capement wheel, as indicated in Fig. 2, whereas the engaging nose of the fixed dog is normally out of engagement with the teeth of the wheel, as indicated in the same figure. The escapement wheel 63 is rigidly secured 70 to a shaft 65 which rotates in bearings 66 and 67 and this shaft carries a feed pinion 68 that is secured thereto and which is in constant mesh with the feed rack 69 secured to the carriage truck. It will therefore be 75 understood that in the movement of the carriage from end to end of the machine, the feed pinion 68, shaft 65 and escapement wheel 63 rotate, and that the relation of these parts is never changed. That is to 80 say, the escapement wheel will always be in the same position when the carriage moves to a fixed point and the position of the escapement wheel depends upon the position of the carriage. The movement of the carriage in the direction of its feed is effected 85 by the letter spacing mechanism when either the space key or the character key is actuated in the following manner:

The depression of a character key, for instance will rock the shaft 29, thereby moving the arm 37 towards the front of the machine. This movement is effective to rock the lever 41 against the tension of its spring 43, thus causing the stop 49 on said lever to turn the 90 fixed dog 52 towards the left in Figs. 2 and 7, the rock-shaft 53 turning with the dog. The effect of this movement is to throw the nose 64 of the fixed dog into the path of one of the teeth of the escapement wheel so that 100 a slight movement of the escapement wheel is afforded before it is arrested by the fixed dog. This movement of the fixed dog as above explained is produced by a depression of a key, and the relation of the fixed and 105 loose dogs, illustrated in Figs. 2 and 7, is at this time maintained by the spring 59 so that the loose dog is thrown out of engagement with the escapement wheel as the fixed dog moves into the path of a tooth thereof. 110 When the loose dog releases the escapement wheel it affords a slight advance movement of the wheel before the wheel is arrested by the fixed dog so as to bring the engaging nose 62 of the loose dog opposite the flat 115 crown 70 on the adjacent tooth of the escapement wheel and at this time the loose dog can no longer arrest that particular tooth of the wheel.

When the pressure on the finger key is released the parts are restored to their normal positions by the various springs 20, 32 and 43 and the fixed dog moves out of the path of the escapement wheel independently of the loose dog which at this time bears against 125 the flat crown 70 on the tooth of the escapement wheel and prevents a movement thereof towards the center of the wheel. As soon, however, as the wheel rotates sufficiently far to carry the tooth, against which the loose 130

dog bears, beyond the loose dog so as to release it, the tension of the spring 59 is effective to force the loose dog, independently of its rock shaft and the fixed dog, into the path 5 of the next advancing tooth of the escapement wheel, thereby affording a letter space movement of the carriage.

During the backward movement of the carriage, or during its movement from left to right, the escapement wheel will be rotated 10 backwardly and the teeth thereof will contact with the under sides of the loose dog, deflecting it out of the path of the teeth of the wheel and against the tension of the 15 spring 59.

It will be understood that the carriage is propelled by a spring drum 71 which is connected at one end to a band 72, the opposite end of which is connected at 73 to an arm 74 20 that is secured to the carriage and the tension of the spring drum is exerted to move the carriage in the direction of its feed, thereby effecting the feed movement of the carriage when the escapement mechanism is actuated, in the manner hereinbefore described.

The bearing 46 is provided with upwardly extending ears 75 that are apertured to receive and constitute bearings for a longitudinally sliding rod 76 that is headed at one end 30 77 to limit the movement thereof. Secured to the sliding rod 76 by a screw 78, is a stop 79 that comprises a bearing portion which is apertured for the passage of the rod therethrough and is extended laterally in order to 35 form a tabulating stop member. The screw 78 is received in a threaded opening in the bearing portion of a stop 79 and bears at its inner end against the rod 76 so as to secure the stop fixed upon the sliding rod 76 and to 40 afford an adjustment of the stop on the rod if necessary. The screw 78 extends beyond the bearing portion of the stop 79, as illustrated in Fig. 3, and constitutes a pin that is seated in an elongated slot 80 in an actuating 45 arm 81. The arm 81 is adjustably secured to a rock shaft 82 which extends from side to side of the machine and outside of one of the corner posts 2. This shaft is received in 50 openings or bearings in the base of the machine so that it is adapted to rock therein and a screw 83 is received in a threaded opening in the hub 84 on the actuating arm and bears at its inner end upon the rock shaft 82, so as to secure the arm to the rock shaft and 55 to afford an adjustment thereof on the shaft when desired. The free end of the rock shaft 82, which extends beyond or outside of the frame of the machine, is rigidly connected to a tabulating key lever 85 which is guided at 60 its forward portion by a guide plate 86 secured by screws 86^a to one of the corner posts of the machine.

A spring 87 is connected at one end to the stop 79 as indicated at 90 and the opposite 65 end of this spring passes loosely through an

eye 91 secured to one side of the actuating lever 81. The tension of the spring is exerted to normally maintain a depending finger 92, which is formed as a part of the stop 79, against the upper side of the shaft 53 so that 70 normally the stop 79 will be maintained with the free or engaging end 79^a thereof in the lowermost position shown in Fig. 2 of the drawings but may be turned up against the tension of the spring 87 and around the longitudinal axis of the movable rod 76, for purposes which will hereinafter appear.

The tabulating key lever and the parts connected thereto are normally maintained in and restored to their normal positions by a 80 contractile spring 94 connected at one end to a corner post of the frame at 95 and at its opposite end to the tabulating key lever. The forward end of this key lever is formed as represented in Fig. 12 with laterally extending supporting portions 96, each of which is apertured centrally at 97 and parallel portions 96^a on the sides of the parts 96 are apertured at 98 to form bearings for pins or pivots 99, each of which is fixed in the 90 bearing openings and passes loosely through an opening 100 in a key stem 101 of the tabulator key. This opening is sufficiently large to permit a lateral swinging movement of the key stem as well as a fore and aft movement 95 thereof around the pivot 98 so that the construction is such that a gimbal or universal joint is formed which permits a movement of nutation of the key head and affords a movement of the key stem in any direction; thus, 100 for instance it will be seen that each key head 102 constitutes four portions or keys *a*, *b*, *c*, *d*, so that a pressure exerted upon the portion *a* will cause the lower end of the associated key stem 101 to be moved diagonally or in the 105 general direction of the portion *c* as well as to cause a downward movement of the stem and the key lever to which it is connected. If the finger of the operator bears upon the portion *b*, the lower end of the key stem will 110 be moved diagonally in the general direction of the portion *d* and the key stem and key lever will at the same time be depressed. It will be understood that the initial pressure exerted upon the key head will tend to deflect the key stem in the manner described and that this movement takes place at the initial portion of the stroke of the key lever, so that it is impossible to depress the key lever without first positioning the key stem 115 in the manner specified. The lower end of each key stem is slightly flattened on four sides, as indicated at 103, and each key stem is received in a guiding opening 104 of a 120 guide block 105 which is secured to the outside of the base of the machine by screws 106. The contour of each of the guiding openings 104 is rectangular in cross section, as indicated in Fig. 19, so that when the lower end of a key stem is moved laterally into a corner 125 130

of its guiding opening, two of the flattened sides 103 on the key stem will cooperate with two side walls of the opening and the lower end of the key stem will be guided in its 5 downward movement. In the lower portion of each guiding opening 104 is an arresting block or abutment 107 which is adjustably secured in place by a set screw 108 that is received in a threaded opening in the block 107 10 and bears at its inner end against the block in order to secure it in place. The upper face of each block 107 is stepped as indicated at 109, 110, 111 and 112, which steps are at four different elevations and extend to the four 15 corners 113 of the guiding opening 104. Each of the blocks 107 is apertured centrally at 114 in order to allow a key stem to pass therein, and to allow each of the key stems to be depressed its fullest extent or past the 20 associated steps or faces 109 to 112 when the key stems are centrally positioned in the guiding openings 104 and the key lever is depressed. Each key stem is surrounded by a weight 115 through which the stem slides 25 loosely and which is beveled at its lower end portion 116 where it is seated in the mouth of a guide opening 104 so as to normally center itself by the weight thereof and to maintain the key stem properly centered in the opening 30 so that it will be in alignment with the central opening 114 in the block 107.

From an examination of Fig. 1, it will be seen that the key stems 101 extend to different depths in the openings 104, and the construction is such that the key stem at the forward end of the key lever may be depressed and brought into contact with its lowest arresting stop 109 before the key stem of the other key is brought to the height of the 40 highest operating stop 112. It will therefore be understood that each key controls the depression of the key lever to four different extents; or that the two keys with their co-operating stops or abutments enable the key 45 lever to be depressed to eight different positions which control the positioning of the tabulating stop 79 so as to arrest the carriage for the decimal, units, tens, hundreds, thousands, tens of thousands, hundreds of 50 thousands and millions positions, as will hereinafter more clearly appear.

It will be understood that the purpose of the weights 115 is, as heretofore explained, to automatically center the key stems 101 55 and normally maintain them centered with the openings 114 in the blocks 107, so that one key stem will pass into its opening 114 and not limit or interfere with the depression of the key lever 85 when it is actuated 60 by the other key head 102.

The stop 79 is provided with a forwardly extending pin 117 that has a cam face 118 at its forward end which is adapted to cooperate with an upwardly extending lug 119 projecting from the loose dog 58, so that a for-

ward movement of the pin brings the cam 118 into contact with the projection of the loose dog, moving the dog against the tension of the spring 59 which normally maintains the dog in the fixed relation with the 70 fixed dog as shown in Fig. 7, where it is in a position to engage and hold the escapement wheel against advance movement. As heretofore explained, the fixed dog 52 is at this time out of engagement with the escapement 75 wheel so that when the cam 118 is actuated by a depression of the key lever 85 it effects a release of the loose dog so that the carriage is disconnected or freed from the escapement mechanism and travels under the 80 tension of the spring drum in the direction of its feed.

The escapement wheel 63 is provided with rearwardly extending clutch teeth 120 that engage like clutch teeth 121 on a stop carrying barrel or member 122 which is loosely mounted on the shaft 65 and is adapted to rotate independently thereof when the clutch members 120 and 121 are disengaged, so as to afford a rotary adjustment of the stop 85 carrying member relatively to the escapement wheel. The stop carrying member 122 is provided with a series of outwardly projecting, radiating and spirally arranged tabulating or denominational stops 123, which in 90 the present instance, are eight in number and are spaced apart so that the distance between the stops corresponds to a letter space movement of the carriage. The construction and relative arrangements of the parts 95 are such, that when the stop 79 is moved forward by a depression of the tabulating key, the stop will be moved to a position where the free end or engaging portion 79^a thereof will be brought into the path of one 100 of the spirally arranged radial denominational stops 123 and will prevent a further rotation of the stop carrier, the escapement wheel, shaft 65, the pinion 68 and will cause an arrest of the carriage. The stop carrying member 122 has its clutch member or teeth 121 normally maintained in engagement with the teeth 120 on the escapement wheel by a coiled expansion spring 124 that is contained within the central hollow portion 110 of the stop carrier, as illustrated in Fig. 11, and bears at one end against the stop carrier and at its opposite end against a sleeve or collar 125 that is secured to the shaft 65 by a screw 126 which extends through the 120 threaded opening in the sleeve and bears at its inner end against the shaft.

A controlling piece or member 127 is loosely seated on the shaft 65 and the hub of this controlling piece is provided with a 125 pinion 128, all portions of the controlling piece being rigidly connected or formed from one piece. The face or disk-like portion of the controlling piece has a stop arresting portion 129 and a cut-away portion 130

130. The stop arresting portion 129 is graduated, as indicated in Fig. 8, with indices which in the present instance are indicated by the numerals "1", "2", "3", "4" 5 and "5" that begin at the upper intersecting point between the cut-away portion and the stop arresting portion in Fig. 8; the numerals extending from right to left when viewed from the rear of the machine. To 10 the rear of the controlling piece, the shaft 65 is formed with an eccentric portion 131 on which is loosely seated an actuator 132 for the controlling piece, said actuator being provided with oppositely disposed pawls or 15 teeth 133 which are adapted to alternately engage the teeth of the pinion 128; the disposition of these pawls with relation to the teeth of the pinion being such that when one of them is in engagement with the pinion, 20 the other is disengaged therefrom. The actuator 132 carries an extended portion 134 that is slotted at 135 where it engages a fixed pin 136 which prevents the actuator from turning but enables it to receive a 25 transverse oscillating movement by reason of the connection thereof with the eccentric 131. An expansion spring 137 is seated in an opening in a bracket 54, as shown in Fig. 3, and bears at its forward end against 30 the actuator 132 so as to normally maintain the teeth 133 thereof in engagement with the teeth of the pinion 128. When, however, a pressure is exerted rearwardly by the 35 fingers of the operator upon the actuator 132, the teeth 133 are disengaged from the pinion and the controlling piece with its pinion is free to be rotated independently of the shaft 65, the actuator 132 and the stop carrier 122, and may be adjusted so as to 40 bring the different indices or numerals "1" to "5" into position to register with the end 79^a of the arresting stop 79. When the controlling piece 127 has been adjusted to the desired position in the manner described, 45 pressure on the actuator 132 may be released and the teeth 133 thereon, or one of the teeth, will be brought into engagement with the pinion 128.

In the present construction the feed pinion 68 is provided with twelve teeth and the escapement wheel 63 is likewise provided with twelve teeth and a complete rotation of the escapement wheel and shaft 65 affords a movement of the carriage twelve 55 letter space distances. It should be understood, however, that these parts may be changed by enlarging or decreasing the number of teeth on the escapement wheel and pinion, so as to provide a greater or a 60 smaller number of letter space movements of the carriage at each rotation of the shaft 65 without departing from the invention. Basing, however, the operation on the construction as shown, it should be understood 65 that each complete rotation of the escape-

ment wheel, the shaft 65 and pinion 68, affords twelve letter space movements of the carriage and this effects a lateral reciprocation of the actuator 132 from right to left and back again, or vice versa, and that this 70 movement of the actuator 132 is in the nature of an escapement device and produces a movement of the controlling piece 127 from one numeral or index thereon to another. That is to say, if the numeral "2" 75 on the controller is in register with the end of the dog or tabulating stop 79, then when twelve letter space movements of the carriage have been effected the controlling piece 80 will have been moved in the direction of the arrow in Fig. 8 to bring the numeral "1" thereon into substantial register with, and to bring the cut-away portion opposite the free end of the stop 79, so that it is free 85 to be moved forward and beyond the controlling piece.

Having described the various features of the construction, I will now describe in detail the operation thereof. It should first be understood that the tabulating mechanism 90 is so constructed and arranged that a depression of any tabulating key is effective to release the carriage and that the carriage may be arrested at the particular denominational position desired as determined by the portion *a*, *b*, *c* or *d* of each key head 102 that is depressed. If desired the mechanism may be set to arrest the carriage at a particular columnar position without the necessity of first arresting the carriage at the preceding 100 columnar positions. That is to say, if desired the mechanism may be set to arrest the carriage at the proper denominational position within a column, such denominational position depending upon the key depression, 105 and the columnar position being determined by the setting of the parts, and it will be unnecessary to first arrest the carriage at preceding columns or columnar positions in order to secure the arrest of the carriage in 110 its proper denominational position within the proper columnar field. Thus, with the twelve letter space distances of the carriage effected by a single rotation of the escapement wheel, as shown and described, the columns are regulated at twelve letter space distances apart and these columns may be located where desired. If, for instance, the carriage in a complete run is adapted to travel seventy letter space distances, which 115 are indicated by the usual scale and pointer shown at 138 and 139 respectively in Fig. 1, then five columns are provided which are twelve letter space distances from the beginning of one column to the beginning of 120 the next. The carriage may be moved back until the pointer is brought to the "0" position on the scale and then the stop carrying member 122 may be disengaged from the escapement wheel and turned so as to adjust 125 130

the stop carrier and the stops thereon to any desired position with reference to the escapement wheel and consequently with reference to the travel of the carriage. In this manner the beginning of the five columns may be varied.

Should the operator desire to employ all five columns, it is merely necessary to adjust the stops 123 as above described to secure the proper locations of the columns and the controlling piece 127 is then adjusted as represented in Fig. 8 so that the terminal of the cut-away portion 130, adjacent to the index numeral "1", is at the stop 79 and allows the free end of the stop to clear the arresting portion 129 on the controlling piece. A depression of the tabulating key lever will then effect a forward movement of the stop 79 and the first portion of this movement is effective to release the loose dog from engagement with the escapement wheel and the continued movement of the stop 79 brings the free end thereof into the path of one of the stops 123 on the stop carrier, thus arresting the carriage at the desired denominational position in the first column from the point where the carriage is arrested, whether it be the first, second, third, fourth or fifth column, and the denominational position of arrest of the carriage will depend on which key is actuated in depressing the key lever. Thus for instance, if the decimal key be depressed, the effect of such depression is to move the free end of the rear key stem diagonally until it is seated in the corner 113 of the guide block opposite the lowest stop 109 with which the key stem is adapted to coöperate. This affords the longest extent of depression of the key lever and moves the arresting stop through the longest distance towards the front of the machine or into the path of the foremost of the spirally arranged stops 123 or the one which is nearest to the front of the machine, and the carriage will move until the stops contact, when the carriage will be arrested at a point that enables an imprint to be made in the decimal position in the column of figures within the proper columnar field of twelve letter spaces. If, however, the millions key is depressed, the stem of the associated key stem will be moved into coöperation with, and will be arrested by, the highest associated stop or abutment 112. The key lever will receive its shortest extent of depression and the tabulating stop 79 will be moved forward throughout its shortest extent of throw and into the path of the rearmost stop 123 or that which is nearest the rear of the machine, and the carriage will be arrested eight letter space distances in advance of the position which it would by a depression of the decimal key, and so on.

It will be seen that during a depression of the key carrying the decimal mark, the other or forward key stem, being maintained cen-

tered by the weight 115, will pass into the opening 104 and will afford no obstruction to the depression of the key lever 85 and when the key carrying the millions mark is depressed the other key stem will remain 70 centered with its opening 114.

The stop 79 is beveled on its lower and outer side so that in the sliding movement thereof, back to the normal position, it rides up or camis over any of the stops 123 that 75 happen to be in its path and the stop 79 during this movement turns on the axial center of the rod 76 and is forced against the tension of the spring 87, which latter tends to move the free end of the stop down to normal position as soon as the stop 79 has cleared the denominational stops 123.

The controlling piece 127 may set so that the carriage will be arrested at the proper denominational position in any of five columns which are twelve letter space distances apart from the beginning of one columnar field to the beginning of the next, and the parts may always be actuated to arrest the carriage at the particular field desired after 90 the controlling piece is set. If, for instance, the operator finishes the writing at "18" on the carriage scale and desires to tabulate in a columnar field beginning at "48", it is merely necessary to depress the necessary denominational key, say, that bearing the mark "1000." and the carriage will be arrested at the proper denominational, or thou-sandths position in the columnar field and those fields which precede it will be excluded. 100 This may be accomplished by releasing the controlling piece 127 from the actuator 132 in the manner hereinbefore described when the carriage is at the beginning of a line and setting the controlling piece so that the 105 numeral "4" is substantially in register with the end of the stop 79 as shown in Fig. 9. A depression of the tabulating key lever through a denominational key, will at this time move the stop 79 forward bringing it 110 into contact with the rear face of the arresting portion 129 of the controlling member and will exert a pressure thereon sufficient to effect a braking action thereon. This same movement of the stop 79 is sufficient to 115 bring the cam 118 into contact with the loose dog, thereby freeing the carriage and enabling it to run in the direction of its feed, while the stop 79, bearing as it does at this time, on the controlling piece, effects a 120 retarding action to prevent the carriage from running too rapidly. It will be understood that the greater the pressure applied to the tabulator, the greater will be the retarding tendency of the stop 79 on the 125 controlling piece and the slower will be the run of the carriage. If the carriage is at the beginning of the line when the carriage is released, it will require four complete revolutions of the escapement wheel to bring the 130

carriage to a point where writing or tabular work may be produced in the fourth columnar field. This rotation of the escapement wheel is effective to produce four complete back and forth movements of the actuator 132 which turns the controlling piece in the direction of the arrow in Fig. 9 from the position shown in said figure to that illustrated in Fig. 8. In this latter position the stop 79 is free to pass the arresting portion 129 and to be projected through the cut-away portion 130 of the controlling member and to be moved into the path of the proper denominational stop as determined by the denominational key depressed, and the carriage will be arrested at the proper denominational position.

From the foregoing description it will be understood that the escapement wheel and set of denominational stops bear a fixed relation to each other and likewise bear a fixed relation to the carriage by reason of the fact that the feed rack 69 and feed pinion 68 are constantly maintained in mesh. This fixed relation may, however, be changed from time to time by disengaging the clutch members 120 and 121 which connect the stop carrier to the escapement wheel, and by rotating the stop carrier with relation to the escapement wheel and again uniting the clutch members in the manner hereinbefore described.

From an inspection of Figs. 15, 16 and 17, it will be seen that each tabulating key stem 101 is rigidly connected to four keys or to a key head having four members *a*, *b*, *c* and *d*, by being riveted thereto at 101^a and that the metallic frame 121 of the key has four perforations, recesses or depressions therein, each having an inwardly projecting circular flange or shoulder 142 that constitutes a seat for an index disk 143 that bears the mark for the key and above the index disk is a protecting disk 144 of transparent material, such as glass or celluloid. Above the transparent disk, each opening has an under-cut circular groove, seat or depression 145, and seated within this groove is a split ring 146 which is shown in detail in Fig. 16. This ring is made of spring metal and has a tendency to spring outwardly and to lock itself in the under-cut groove and to project over the transparent disk and thus lock and secure the disks 143 and 144 in position in the key head. It will thus be seen that a simple and efficient key head structure is provided wherein the parts can be readily and securely united or assembled and that the ring 142 may be readily removed when desired to replace either or both of the disks 143 and 144 which are secured in place by the ring.

From the foregoing description it will be understood that the tabulating devices co-operate with the carriage feed mechanism to effect an arrest of the carriage at the proper

denominational positions. That is to say, the denominational stops are connected to the escapement mechanism and an arrest of the denominational stops effects an arrest of the escapement wheel and thus arrests the carriage. It will likewise be observed that the controlling device 127 constitutes automatically actuated blocking means for preventing an actuation of the tabulating devices to interpose the stop 79 in the path of one of the denominational stops 123 until the carriage has reached a predetermined point in the travel thereof and that the point in the travel of the carriage when the stop 79 may be so interposed to arrest the movement of the carriage, may be varied by an adjustment of the controlling device 127.

It should be understood that from certain aspects of my invention denominational tabulating mechanism as such need not be employed. Thus, for instance, if a single stop 123 is employed and the stop 79 be given a single extent of throw an ordinary tabulating device is provided wherein the controlling device 127 may be set to prevent the arrest of the carriage at any columnar position preceding the one for which the controlling device is set.

The escapement mechanism *per se* is not claimed herein but is claimed in a separate application filed by me March 21st, 1903, Serial No. 148,941. The carriage releasing mechanism *per se* shown in part herein is not claimed in this case but is claimed in a separate application filed by me March 21st, 1903, Serial No. 148,942.

What I claim as new and desire to secure by Letters Patent, is:—

1. In a typewriting machine and tabulating mechanism, the combination of a carriage, carriage feed mechanism including a feed rack and means for controlling the feed of the rack, and denominational tabulating devices that co-operate with a part of said means for controlling the feed of the rack to effect an arrest of the carriage at the proper denominational position.

2. In a typewriting machine and tabulating mechanism, the combination of a carriage, carriage feed mechanism including a feed rack and means for controlling the feed of the rack, denominational tabulating devices that co-operate with a part of said means for controlling the feed of the rack to effect an arrest of the carriage at the proper denominational position, and means for automatically effecting a release of the carriage when said tabulating mechanism is actuated.

3. In a typewriting machine and tabulating mechanism, the combination of a carriage, a feed pinion therefor, and tabulating devices operative through the feed pinion to effect an arrest of the carriage at a predetermined position.

4. In a typewriting machine and tabulat-

- ing mechanism, the combination of a carriage, a feed pinion therefor, tabulating devices operative through the feed pinion to effect an arrest of the carriage at a predetermined position, and means for automatically effecting a release of the carriage when said tabulating devices are actuated.
5. In a typewriting machine and tabulating mechanism, the combination of a carriage, carriage escapement devices including an escapement wheel, and tabulating devices for arresting said carriage at a predetermined point by effecting an arrest of the escapement wheel.
10. 6. In a typewriting machine and tabulating mechanism, the combination of a carriage, carriage escapement devices including an escapement wheel, tabulating devices for arresting said carriage at a predetermined point through the escapement wheel, and means for releasing said escapement wheel when the tabulating devices are actuated.
15. 7. In a typewriting machine and tabulating mechanism, the combination of a carriage, a feed rack carried thereby, a feed pinion engaging said rack, an escapement wheel operatively connected to said feed pinion, and tabulating devices for controlling the movement of the escapement wheel and thus effecting an arrest of the carriage at a predetermined position.
20. 8. In a typewriting machine and tabulating mechanism, the combination of a carriage, a feed rack carried thereby, a feed pinion engaging said rack, an escapement wheel operatively connected to said feed pinion, tabulating devices for controlling the movement of the escapement wheel and thus effecting an arrest of the carriage at a predetermined position, and means for automatically releasing the carriage when said tabulating devices are operated.
25. 9. In a typewriting machine and tabulating mechanism, the combination of a carriage, a series of spirally arranged tabulating stops that is rotated by the travel of the carriage, and a tabulating stop that coöperates therewith to arrest the carriage.
30. 10. In a typewriting machine and tabulating mechanism, the combination of a carriage, a series of spirally arranged tabulating stops that is rotated by the travel of the carriage, a tabulating stop that coöperates therewith to arrest the carriage, key actuated means for moving said stop and one of the series of stops into the path of the other, and means for releasing the carriage when one of said stops is moved into the path of the other.
35. 11. In a typewriting machine and tabulating mechanism, the combination of a carriage, a series of denominational stops rotated by the travel of the carriage, and a stop that is adapted to coöperate with said denominational stops to arrest the carriage in different denominational positions.
40. 12. In a typewriting machine and tabulating mechanism, the combination of a carriage, a series of denominational stops rotated by the travel of the carriage, an arresting stop that is adapted to coöperate with said denominational stops to arrest the carriage at different denominational positions, and means for automatically releasing the carriage when the arresting stop and one of the denominational stops receives a relative movement to coöperate one with the other.
45. 13. In a typewriting machine and tabulating mechanism, the combination of a carriage, carriage escapement devices including an escapement wheel, a series of denominational stops, and a coöperating stop, one, the denominational stops or the coöperating stop, being operatively connected to said escapement wheel for rotation therewith.
50. 14. In a typewriting machine and tabulating mechanism, the combination of a carriage, carriage escapement devices including an escapement wheel, a series of denominational stops operatively connected to rotate with said escapement wheel, a coöperating arresting stop, and means for automatically releasing the carriage when said arresting stop is moved into position to coöperate with said denominational stops.
55. 15. In a typewriting machine and tabulating mechanism, the combination of a carriage, a series of denominational stops that is rotated by the travel of the carriage, a coöperating stop, and means for adjusting said stops relatively one to the other, to afford an arrest of the carriage at different denominational positions in accordance with the particular denominational stop which is engaged.
60. 16. In a typewriting machine and tabulating mechanism, the combination of a carriage, a part comprising a series of spirally arranged denominational stops, another part comprising a coöperating stop, one of said parts being rotated by the travel of the carriage, and means for affording an adjustment of one of said parts relatively to the other.
65. 17. In a typewriting machine and tabulating mechanism, the combination of a carriage, a set of denominational stops rotated by the travel of the carriage, a coöperating stop, and means for adjusting the set of denominational stops.
70. 18. In a typewriting machine and tabulating mechanism, the combination of a carriage, a set of denominational stops, means controlled by the travel of the carriage for rotating said denominational stops, a coöperating stop, and means for adjusting the set of denominational stops relatively to the means for rotating them.
75. 19. In a typewriting machine and tabulating mechanism, the combination of a carriage, a series of denominational stops rotated by the travel of the carriage, a coöperating stop, and means for adjusting the set of denominational stops relatively to the means for rotating them.
80. 20. 130. 21. In a typewriting machine and tabulating mechanism, the combination of a carriage, a series of denominational stops rotated by the travel of the carriage, a coöperating stop, and means for adjusting the set of denominational stops relatively to the means for rotating them.

- riage, a series of spirally arranged denominational stops rotated by the travel of the carriage, and a coöperating stop.
20. In a typewriting machine and tabulating mechanism, the combination of a carriage, escapement devices therefor including an escapement wheel, a set of denominational stops adjustably connected to said escapement wheel, and a coöperating stop.
- 10 21. In a typewriting machine and tabulating mechanism, the combination of a carriage, escapement devices therefor including an escapement wheel, a set of spirally arranged denominational stops adjustably connected to said escapement wheel, a coöperating stop, and means for automatically releasing the carriage when a relative movement of the stops is effected to bring them into coöperative relation.
- 20 22. In a typewriting machine and tabulating mechanism, the combination of a carriage, escapement devices including an escapement wheel having a clutch member, a tabulating stop having a coöperating clutch member, and a coöperating tabulating stop.
- 30 23. In a typewriting machine and tabulating mechanism, the combination of a carriage, escapement devices including an escapement wheel having a clutch member, a coöperating clutch member carrying a series of denominational stops, and a coöperating tabulating stop.
- 35 24. In a typewriting machine and tabulating mechanism, the combination of a carriage, escapement devices including an escapement wheel having a clutch member, a coöperating clutch member carrying a series of spirally arranged denominational stops, a coöperating tabulating stop, and means for automatically releasing the carriage when the stops are moved relatively to one another to bring them into coöperation.
- 40 25. In a typewriting machine and tabulating mechanism, the combination of a carriage, a series of denominational stops rotated by the travel of the carriage, means for adjusting the series of stops relatively to the means which rotate the stops and without destroying the relation between the denominational stops, and a coöperating tabulating stop.
- 45 26. In a typewriting machine and tabulating mechanism, the combination of a carriage, a feed rack therefor, a feed pinion cooperating with the rack, an escapement wheel operatively connected to the feed pinion, a series of denominational stops connected to the escapement wheel, and a coöperating tabulating stop.
- 50 27. In a typewriting machine and tabulating mechanism, the combination of a carriage, a feed rack therefor, a feed pinion cooperating with the rack, an escapement wheel operatively connected to the feed pinion, a series of denominational stops connected
- to the escapement wheel, means for effecting an adjustment between the series of denominational stops and the escapement wheel, a coöperating tabulating stop, and means for effecting a release of the carriage when said stops are moved relatively one to another to bring them into coöperation.
- 55 28. In a typewriting machine and tabulating mechanism, the combination of a carriage, a feed rack therefor, a feed pinion cooperating with the rack, an escapement wheel operatively connected to the feed pinion, a clutch member carried by said escapement wheel, a coöperating clutch member having a series of spirally arranged denominational stops, a coöperating stop, and means for automatically releasing the escapement wheel when the stops are being brought into coöperation.
- 60 29. In a typewriting machine and tabulating mechanism, the combination of a carriage, an escapement wheel operatively connected thereto, feed dogs that coöperate with the escapement wheel, tabulating devices connected to said escapement wheel, coöperating tabulating devices for effecting an arrest of the carriage at a predetermined point by arresting the escapement wheel, and means for automatically effecting a release of the escapement wheel from said dogs when the tabulating devices are actuated.
- 65 30. In a typewriting machine and tabulating mechanism, the combination with a carriage and tabulating devices, of means for preventing an actuation of the tabulating devices until the carriage reaches a predetermined point in its travel.
- 70 31. In a typewriting machine and tabulating mechanism, the combination with a carriage and tabulating devices, of means for preventing an actuation of the tabulating devices until the carriage reaches a predetermined point in its travel, and adjustable means for determining at what point in the travel of the carriage said tabulating devices may be capable of actuation.
- 75 32. In a typewriting machine and tabulating mechanism, the combination with a carriage and tabulating devices, of adjustable blocking means for preventing an actuation of the tabulating devices until the carriage reaches a predetermined point in its travel.
- 80 33. In a typewriting machine and tabulating mechanism, the combination with a carriage and tabulating devices, of automatically movable blocking means for preventing an actuation of the tabulating devices until the carriage reaches a predetermined point in its travel, and means for effecting an adjustment of said blocking means so as to determine at what point in the travel of the carriage said tabulating devices may be capable of actuation.
- 85 34. In a typewriting machine and tabulating mechanism, the combination with a carriage

riage and tabulating devices, of blocking means operatively connected to the carriage so as to be moved thereby, for preventing an actuation of the tabulating devices until the carriage has reached a predetermined point in its travel.

35. In a typewriting machine and tabulating mechanism, the combination with a carriage and tabulating devices, of blocking means operatively connected to the carriage so as to be moved thereby for preventing an actuation of the tabulating devices until the carriage has reached a predetermined point in its travel, and means for affording an adjustment of the blocking means.

36. In a typewriting machine and tabulating mechanism, the combination with a carriage and tabulating devices, of means for preventing an actuation of the tabulating devices until the carriage reaches a predetermined point in its travel, and indicating means to determine the setting of said adjustable means.

37. In a typewriting machine and tabulating mechanism, the combination with a carriage and tabulating devices, of adjustable blocking means for preventing an actuation of the tabulating devices until the carriage reaches a predetermined point in its travel, and indicating means for determining the setting of said adjustable means.

38. In a typewriting machine and tabulating mechanism, the combination with a carriage and tabulating devices, of blocking means operatively connected to the carriage so as to be moved thereby, for preventing an actuation of the tabulating devices until the carriage has reached a predetermined point in its travel, and indicating means to determine a proper setting of said adjusting means.

39. In a typewriting machine and tabulating mechanism, the combination of a carriage, tabulating devices, means for preventing an actuation of the tabulating devices to arrest the carriage until it has reached a predetermined point in its travel, and automatically actuated means for retarding the movement of the carriage during the travel thereof in the direction of its feed.

40. In a typewriting machine and tabulating mechanism, the combination of a carriage, key controlled tabulating devices, means for preventing an actuation of the tabulating devices to arrest the carriage until it has reached a predetermined point in its travel, and means actuated by the key which controls the tabulating devices for retarding the movement of the carriage during the travel thereof in the direction of its feed.

41. In a typewriting machine and tabulating mechanism, the combination of a carriage, key controlled tabulating devices, means for preventing an actuation of the tabulating devices to arrest the carriage un-

til it has reached a predetermined point in its travel, and means actuated by the key which controls the tabulating devices for retarding the movement of the carriage during the travel thereof in the direction of its feed, said retarding means being variably applied to regulate the speed of travel of the carriage accordingly as the amount of pressure applied to said key is varied.

42. In a typewriting machine and tabulating mechanism, the combination of a carriage, means for releasing said carriage, tabulating devices that control the actuation of the carriage releasing means, means that afford an operation of the carriage releasing means but prevent an actuation of the tabulating devices to arrest the carriage until it has reached a predetermined point in its travel, and means that are brought into operation when the carriage is released for retarding the movement of the carriage during the travel thereof in the direction of its feed.

43. In a typewriting machine and tabulating mechanism, the combination of a carriage, carriage feed mechanism, denominational tabulating devices that coöperate with the carriage feed mechanism to effect an arrest of the carriage at the proper denominational position through said carriage feed mechanism, and means for preventing an actuation of the tabulating devices to arrest the carriage until it has reached a predetermined point in its travel.

44. In a typewriting machine and tabulating mechanism, the combination of a carriage, carriage feed mechanism, denominational tabulating devices that coöperate with the carriage feed mechanism to effect an arrest of the carriage at the proper denominational position through said carriage feed mechanism, means for automatically effecting a release of the carriage when said tabulating mechanism is actuated, and means which afford a release of the carriage but prevent an actuation of the tabulating devices to arrest the carriage until it has reached a predetermined point in its travel.

45. In a typewriting machine and tabulating mechanism, the combination of a carriage, carriage escapement devices including an escapement wheel, tabulating devices for arresting said carriage at a predetermined point through an arrest of the escapement wheel, and means for preventing an actuation of the tabulating devices to arrest the carriage until it has reached a predetermined point in its travel.

46. In a typewriting machine and tabulating mechanism, the combination of a carriage, carriage escapement devices including an escapement wheel, tabulating devices for arresting said carriage at a predetermined point through an arrest of the escapement wheel, means for releasing said escape-

ment wheel when the tabulating devices are actuated, and means which afford a release of the carriage but prevent an actuation of the tabulating devices to arrest the carriage 5 until it has reached a predetermined point in its travel.

47. In a typewriting machine and tabulating mechanism, the combination of a carriage, a feed rack carried thereby, a feed 10 pinion engaging said rack, an escapement wheel operatively connected to said feed pinion, tabulating devices for controlling the movement of the escapement wheel and thus effecting an arrest of the carriage at a 15 predetermined position, and means for preventing an actuation of the tabulating devices until the carriage has reached a predetermined point in its travel.

48. In a typewriting machine and tabulating mechanism, the combination of a carriage, a feed rack carried thereby, a feed 20 pinion engaging said rack, an escapement wheel operatively connected to said feed pinion, tabulating devices for controlling the 25 movement of the escapement wheel and thus effecting an arrest of the carriage at a predetermined position, means for automatically releasing the carriage when said tabulating devices are operated, and means which 30 afford a release of the carriage but prevent an actuation of the tabulating devices to arrest the carriage until it has reached a predetermined point in its travel.

49. In a typewriting machine and tabulating mechanism, the combination of a carriage, a tabulating stop that is rotated by 35 the travel of the carriage, an arresting tabulating stop that coöperates with the first mentioned stop to arrest the carriage at a 40 predetermined position, and means which prevent an actuation of the arresting stop to arrest the carriage until it has reached a predetermined point in its travel.

50. In a typewriting machine and tabulating mechanism, the combination of a carriage, a tabulating stop that is rotated by 45 the travel of the carriage, an arresting tabulating stop that coöperates with the first mentioned stop to arrest the carriage at a 50 predetermined position, controlling means which prevent an actuation of the arresting stop to arrest the carriage until it has reached a predetermined point in its travel, and means for affording an adjustment of 55 said controlling means, so that the point in the travel of the carriage when the stops may be brought into cooperative relation may be varied.

51. In a typewriting machine and tabulating mechanism, the combination of a carriage, a tabulating stop that is rotated by 60 the travel of the carriage, an arresting tabulating stop that coöperates with the first mentioned stop to arrest the carriage at a

predetermined position, means which prevent an actuation of the arresting stop to arrest the carriage until it has reached a predetermined point in its travel and afford a braking action against the free run of the carriage. 65

52. In a typewriting machine and tabulating mechanism, the combination of a carriage, a tabulating stop that is rotated by the travel of the carriage, a tabulating stop that coöperates therewith to arrest the carriage at a predetermined position, key actuated means for moving one of said stops into the path of the other, means for releasing the carriage when one of said stops is moved to position it in the path of the other, 80 and means which afford a release of the carriage through said key actuated means but prevent an interpositioning of one of said stops in the path of the other until the carriage reaches a predetermined point in its 85 travel.

53. In a typewriting machine and tabulating mechanism, the combination of a carriage, a tabulating stop that is rotated by 90 the travel of the carriage, a tabulating stop that coöperates therewith to arrest the carriage at a predetermined position, key actuated means for moving one of said stops into the path of the other, means for releasing the carriage when one of said stops is 95 moved to position it in the path of the other, and controlling means which afford a release of the carriage through said key actuated means but prevent an interpositioning of one of said stops in the path of the other until the carriage reaches a predetermined point in its 100 travel, said controlling means affording a braking action to prevent a free travel of the carriage when the key actuated means are operated. 105

54. In a typewriting machine and tabulating mechanism, the combination of a carriage, a series of denominational stops rotated by the travel of the carriage, a stop that is adapted to coöperate with said denominational stops to arrest the carriage at different denominational positions, and means for preventing the said stops from being brought into coöperation until the carriage has reached a predetermined point in its travel. 110

55. In a typewriting machine and tabulating mechanism, the combination of a carriage, a series of denominational stops rotated by the travel of the carriage, an arresting stop that is adapted to coöperate with 115 said denominational stops to arrest the carriage at different denominational positions, means for automatically releasing the carriage when the arresting stop and the denominational stops receive a relative movement to coöperate one with the other, and means which afford a release of the carriage but prevent the stops from being brought 120

into coöperative relation until the carriage has reached a predetermined point in the travel thereof.

56. In a typewriting machine and tabulating mechanism, the combination of a carriage, a series of denominational stops rotated by the travel of the carriage, an arresting stop that is adapted to coöperate with said denominational stops to arrest the carriage at different denominational positions, means for automatically releasing the carriage when the arresting stop and the denominational stops receive a relative movement to coöperate one with the other, controlling means which afford a release of the carriage but prevent the stops from being brought into coöperative relation until the carriage has reached a predetermined point in the travel thereof, and means for affording an adjustment of the controlling means so that the stops may be brought into coöperative relation at different points in the travel of the carriage.

57. In a typewriting machine and tabulating mechanism, the combination of a carriage, carriage escapement devices including an escapement wheel, a series of denominational stops, a coöperating stop; one, the denominational stops or the coöperating stop, being operatively connected to said escapement wheel for rotation therewith, key actuated means for bringing the denominational stops and the coöperating stop into coöperative relation, and means for preventing the stops from being brought into coöperative relation until the carriage has reached a predetermined point in its travel.

58. In a typewriting machine and tabulating mechanism, the combination of a carriage, carriage escapement devices including an escapement wheel, a series of denominational stops, a coöperating stop; one, the denominational stops or the coöperating stop being operatively connected to said escapement wheel for rotation therewith, key actuated means for bringing the denominational stops and the actuating stop into coöperative relation, controlling means for preventing the stops from being brought into coöperative relation until the carriage has reached a predetermined point in its travel, means for effecting a relative adjustment of the parts, so that the controlling means enable the stops to be brought into coöperative relation at different points in the travel of the carriage.

59. In a typewriting machine and tabulating mechanism, the combination of a carriage, tabulating devices, controlling means for preventing the tabulating devices from being brought into coöperative relation until the carriage has reached a predetermined point in its travel, and means controlled by the travel of the carriage for automatically moving said controlling means.

60. In a typewriting machine and tabu-

lating mechanism, the combination of a carriage, tabulating devices, controlling means preventing the tabulating devices from being brought into coöperative relation until the carriage has reached a predetermined point in its travel, means controlled by the travel of the carriage for automatically moving said controlling means, and means for affording an adjustment of the controlling means with reference to the moving means therefor.

61. In a typewriting machine and tabulating mechanism, the combination of a carriage, a denominational stop device, a coöperating stop, one of said parts being rotated by the travel of the carriage, means for affording an adjustment of one of said parts relatively to the other, and means for preventing said stops from being brought into coöperative relation until the carriage has reached a predetermined point in its travel.

62. In a typewriting machine and tabulating mechanism, the combination of a carriage, a denominational stop device, a coöperating stop, one of said parts being rotated by the travel of the carriage, means for affording an adjustment of one of said parts relatively to the other, controlling means for preventing said stops from being brought into coöperative relation until the carriage has reached a predetermined point in its travel, and means for affording an adjustment of said controlling means, so that the stops may be brought into coöperative relation at various points in the travel of the carriage.

63. In a typewriting machine and tabulating mechanism, the combination of a carriage, a set of denominational stops rotated by the travel of the carriage, a coöperating stop, means for adjusting the set of denominational stops, and means for preventing said stops from being brought into coöperative relation until the carriage has reached a predetermined point in its travel.

64. In a typewriting machine and tabulating mechanism, the combination of a carriage, a set of denominational stops rotated by the travel of the carriage, a coöperating stop, means for adjusting the set of denominational stops, controlling means for preventing said stops from being brought into coöperative relation until the carriage has reached a predetermined point in its travel, and means for affording an adjustment of said controlling means, so that the stops may be brought into coöperative relation at various points in the travel of the carriage.

65. In a typewriting machine and tabulating mechanism, the combination of a carriage, a series of spirally arranged denominational stops rotated by the travel of the carriage, a coöperating stop, and means for preventing the coöperation of said stops

until the carriage has reached a predetermined point in its travel.

66. In a typewriting machine and tabulating mechanism, the combination of a carriage, a series of spirally arranged denominational stops rotated by the travel of the carriage, a coöperating stop, means for preventing the coöperation of said stops until the carriage has reached a predetermined point in its travel, and means for affording a relative adjustment of the parts so that the stops may be brought into coöperative relation at different points in the travel of the carriage.

67. In a typewriting machine and tabulating mechanism, the combination of a carriage, a series of spirally arranged denominational stops rotated by the travel of the carriage, a coöperating stop, and controlling means for preventing the coöperation of said stops until the carriage has reached a predetermined point in its travel, said controlling means affording a braking action to retard the run of the carriage.

68. In a typewriting machine and tabulating mechanism, the combination of a carriage, escapement devices therefor including an escapement wheel, a set of spirally arranged denominational stops adjustably connected to said escapement wheel, a coöperating stop, means for automatically releasing the carriage when a relative movement of the stops is effected to bring them into coöperative relation, and means which prevent the stops from being brought into coöperative relation until the carriage reaches a predetermined point in its travel.

69. In a typewriting machine and tabulating mechanism, the combination of a carriage, escapement devices therefor including an escapement wheel, a set of spirally arranged denominational stops adjustably connected to said escapement wheel, a coöperating stop, means for automatically releasing the carriage when a relative movement of the stops is effected to bring them into coöperative relation, controlling means which prevent the stops from being brought into coöperative relation until the carriage reaches a predetermined point in its travel, means for affording an adjustment of the controlling means, and means controlled by the travel of the carriage for automatically moving said controlling means.

70. In a typewriting machine and tabulating mechanism, the combination of a carriage, an escapement wheel operatively connected thereto, feed dogs that coöperate with the escapement wheel, tabulating devices connected to said escapement wheel, coöperating tabulating devices for effecting an arrest of the carriage at a predetermined point by arresting the escapement wheel, means for automatically effecting a release of the escapement wheel from said dogs when the tabulat-

ing devices are actuated, and means for preventing the tabulating devices from being brought into coöperation until the carriage reaches a predetermined point in its travel.

71. In a typewriting machine and tabulating mechanism, the combination of a carriage, an escapement wheel operatively connected thereto, feed dogs that coöperate with the escapement wheel, tabulating devices connected to said escapement wheel, coöperating tabulating devices for effecting an arrest of the carriage at a predetermined point by arresting the escapement wheel, means for automatically effecting a release of the escapement wheel from said dogs when the tabulating devices are actuated, controlling means for preventing the tabulating devices from being brought into coöperation until the carriage reaches a predetermined point in its travel, and means for affording an adjustment of said controlling means so that the tabulating devices may be brought into coöperation at various points in the travel of the carriage.

72. In a typewriting machine and tabulating mechanism, the combination of a carriage, tabulating devices for arresting the carriage at any of a plurality of columnar positions, and means for preventing the tabulating devices from being brought into coöperative relation until the carriage has reached a predetermined columnar position.

73. In a typewriting machine and tabulating mechanism, the combination of a carriage, tabulating devices for arresting the carriage at any of a plurality of columnar positions, controlling means for preventing the tabulating devices from being brought into coöperative relation until the carriage has reached a predetermined columnar position, and means for adjusting said controlling means so that the tabulating devices may be brought into coöperation when the carriage has reached any particular columnar position.

74. In a typewriting machine and tabulating mechanism, the combination of a carriage, tabulating devices for arresting the carriage at any of a plurality of columnar positions, controlling means for preventing the tabulating devices from being brought into coöperative relation until the carriage has reached a predetermined columnar position, and means for adjusting said controlling means so that the tabulating devices may be brought into coöperation when the carriage has reached any particular columnar position, said controlling means acting as a retarding means to prevent a free run of the carriage.

75. In a typewriting machine and tabulating mechanism, the combination of a carriage, carriage releasing mechanism, tabulating stops, key actuated means for controlling the carriage releasing mechanism and the in-

terpositioning of one tabulating stop in the path of another, and means which afford an actuation of the carriage releasing mechanism but prevent the interpositioning of the stops one in the path of the other until the carriage has reached a predetermined point in its travel.

76. In a typewriting machine and tabulating mechanism, the combination of a carriage, carriage releasing mechanism, tabulating stops, key actuated means for controlling the carriage releasing mechanism and the interpositioning of the one tabulating stop in the path of another, controlling means which afford an actuation of the carriage releasing mechanism but prevent the interpositioning of the stops one in the path of the other until the carriage has reached a predetermined point in its travel, and means for adjusting said controlling means, to determine when said stops may be interposed one in the path of the other.

77. In a typewriting machine and tabulating mechanism, the combination of tabulating devices, a key lever therefor, and a key connected to said lever and movable relatively thereto, the different positions to which said key is moved relatively to the key lever determining the extent of movement of the key lever.

78. In a typewriting machine and tabulating mechanism, the combination of tabulating devices, a key lever that is moved in but one direction to control the tabulating devices, and a key connected to said lever to move therewith and to be movable relatively thereto, the different positions to which said key is moved relatively to the key lever determining the extent of movement of said lever.

79. In a typewriting machine and tabulating mechanism, the combination of a carriage, denominational tabulating devices, a key lever for actuating said tabulating devices to arrest the carriage at different denominational positions, a key carried by and movable relatively to said key lever, and a plurality of stops with which said key is adapted to be brought into contact to determine the denominational positioning of the tabulating devices.

80. In a typewriting machine and tabulating mechanism, the combination of a carriage, carriage releasing devices, denominational tabulating devices, and a single key lever movable in one direction to actuate the carriage releasing devices, to set the tabulating devices to arrest the carriage at the proper denominational position and to move the tabulating devices into coöperative relation, said tabulating devices including a series of spirally arranged denominational stops and a coöperating stop device, one of the coöperating stop and series of stop members being rotated by the carriage.

81. In a typewriting machine and tabulating mechanism, the combination of a carriage, denominational tabulating devices, a key lever for actuating said tabulating devices to arrest the carriage at different denominational positions, a key carried by and movable relatively to said lever, a plurality of stops with which said key is adapted to be brought into contact to determine the denominational positioning of the tabulating devices, and means controlled by said key lever for releasing the carriage.

82. In a typewriting machine and tabulating mechanism, the combination of a carriage, tabulating devices, a key lever therefor, and a key connected to said key lever and movable relatively thereto, the different positions to which said key is moved relatively to the key lever determining the extent of movement of said lever, and means controlled by the movement of the key lever for releasing the carriage.

83. In a typewriting machine and tabulating mechanism, the combination of a carriage, tabulating devices, a key lever for controlling said tabulating devices, and a key connected to said lever by a universal joint, the movement of the key on the universal joint determining the extent of movement of the key lever.

84. In a typewriting machine and tabulating mechanism, the combination of a carriage, tabulating devices, a key lever therefor, and a key that has a movement of nutation on the key lever and which determines the extent of movement of said lever.

85. In a typewriting machine and tabulating mechanism, the combination of a carriage, denominational tabulating devices, a key lever that controls the relative positioning of the tabulating devices, so that the carriage may be arrested at different denominational positions, and a key carried by and having a movement of nutation on the key lever, to determine the extent to which the key lever may be moved.

86. In a typewriting machine and tabulating mechanism, the combination of a carriage, carriage releasing means, denominational tabulating devices, a key lever that controls the carriage releasing means and relative positioning of the tabulating devices, so that the carriage may be released and arrested at different denominational positions by a movement of the key lever in one direction, and a key carried by and having a movement of nutation on the key lever, to determine the extent to which the key lever may be moved and thereby determine the denominational position of arrest of the carriage.

87. In a typewriting machine and tabulating mechanism, the combination of a carriage, denominational tabulating devices, a key lever that controls the relative position-

- ing of the tabulating devices, so that the carriage may be arrested at different denominational positions, a key carried by and provided with a plurality of indices and having a movement of nutation on the key lever, and a plurality of stops with which said key coöperates. 5
88. In a typewriting machine and tabulating mechanism, the combination of tabulating devices, a key that controls the tabulating devices and has a movement of nutation, and a plurality of stops that coöperate with said key. 10
89. In a typewriting machine and tabulating mechanism, the combination of tabulating devices, a guide block, and a key for controlling said tabulating devices and which is guided by said guide block, said key having a movement of nutation. 15
90. In a typewriting machine and tabulating mechanism, the combination of tabulating devices, a guide block, a key for controlling said tabulating devices and which is guided by said guide block, said key having a movement of nutation, and stops to which the guides in the guide block direct the key. 20
91. In a typewriting machine and tabulating mechanism, the combination of tabulating devices, a guide block, a key for controlling said tabulating devices and which is guided by said guide block, said key having a movement of nutation, stops to which the guides in the guide block direct the key, and a weight which normally maintains the key centered in the guide block. 25
92. In a typewriting machine and tabulating mechanism, the combination of tabulating devices, a key for controlling said devices and which has a movement of nutation, finger bearing portions at different sides of said key, and a weight for normally maintaining said key centered. 30
93. In a typewriting machine and tabulating mechanism, the combination of a carriage, an escapement wheel therefor, and key actuated denominational tabulating devices for arresting the carriage at a predetermined denominational position by effecting an arrest of the escapement wheel. 45
94. In a typewriting machine and tabulating mechanism, the combination of a carriage, an escapement wheel therefor, and tabulating devices for arresting the carriage at any predetermined denominational position within a predetermined columnar field by effecting an arrest of the escapement wheel. 55
95. In a typewriting machine and tabulating mechanism, the combination of a car-
- riage, step-by-step carriage feed devices including a rotative part, and key-controlled denominational tabulating means coöperative with said rotative part of the step-by-step carriage feed devices to arrest the carriage in the proper denominational position. 65
96. In a typewriting machine and tabulating mechanism, the combination of a carriage, step-by-step carriage feed devices, key-controlled tabulating means coöperative with certain of said step-by-step carriage feed devices to arrest the carriage in any predetermined denominational position within a columnar field, said tabulating means including stops, and means separate from said stops for determining at what columnar field in the travel of the carriage said stops may become effective. 70
97. In a typewriting machine and tabulating mechanism, the combination of a carriage, an escapement wheel, and denominational tabulating devices including a member which is adapted to be operatively connected to said escapement wheel to move therewith, and key-controlled variable means for arresting said member to determine the denominational position of arrest of the carriage. 75
98. In a typewriting machine and tabulating mechanism, the combination of a carriage, tabulating devices, and automatically actuated controlling means for preventing said tabulating devices from being brought into coöperative relation until a predetermined columnar field has been reached. 80
99. In a typewriting machine and tabulating mechanism, the combination of a carriage, tabulating devices, and automatically actuated controlling means for preventing said tabulating devices from being brought into coöperative relation until a predetermined columnar field has been reached, said controlling means being actuated by the movement of the carriage. 85
100. In a typewriting machine and tabulating mechanism, the combination of a carriage, a series of radiating denominational stops which are turned by the movement of the carriage, and key-controlled means coöperating with said radiating stops to arrest the carriage in the desired denominational position determined by the actuation of said key-controlled means. 100
